IRONING PRESS APPARATUS FOR CLOTHES,
TEXTILE FABRICS, OR THE LIKE

Percy James Drain, Roseville, near Sydney, New South Wales, Australia, assignor to George Eldridge Tidbury, Alexandria, near Sydney, New South Wales, Australia

Application October 4, 1951, Serial No. 249,722
In Australia October 25, 1950

27 Claims. (Cl. 38—34)

1

This invention relates to an improved ironing press apparatus for clothes, textile fabrics or the like.

One form of ironing press of the present invention comprises a supporting frame, an ironing board mounted on the supporting frame, an iron carrying manually operable actuating arm pivoted to the frame, an iron pivoted to the actuating arm, the iron being so biased that its front edge engages the ironing board first and disengages the ironing board last, and spring actuated toggle means for supporting the iron carrying arm in a raised position, manually operable means being connected to the toggle means for changing the spring action thereof to force the iron into spring pressed engagement with the work upon the ironing board.

In another form of the invention, the ironing board is mounted at angle on springs, so that the board slopes downwardly toward the operator. When the iron is brought down upon the work, it slides forwardly toward the operator, thereby providing an additional smoothing action for pressing the work.

Other features of the invention are hereinafter referred to.

In order that the invention may be better understood and carried into effect, certain illustrative embodiments of the invention will now be more particularly described with reference to the accompanying drawings, in which:

Fig. 1 is a perspective view of one construction of the apparatus;

Fig. 2 is an elevation of the apparatus with the actuating arm in its raised position;

Fig. 3 is an elevation of the apparatus with the actuating arm lowered for pressing the work;

Fig. 4 is an enlarged sectional elevation on plane 4—4, Fig. 1;

Fig. 5 is a similar view on line 5—5, Fig. 4;

Fig. 6 is an enlarged sectional elevation on plane 6—6, Fig. 1;

Fig. 7 is a similar view on line 7—7, Fig. 6;

Fig. 8 is a plan view of the ironing element with the top cover plate removed therefrom;

Fig. 9 is a cross-section on line 9—9, Fig. 8;

Fig. 10 is an enlarged plan view of the manually operable actuating arm;

Fig. 11 is a cross-section on line 11—11, Fig. 10;

Fig. 12 is an enlarged elevation of a coil spring and its anchorage mountings when in a neutral position located between its extreme operative positions;

Figs. 13 and 14 are similar views of a coil spring in both its extreme operating positions;

2

Fig. 15 is an elevation view of a modified construction of the apparatus;

Fig. 16 is an enlarged sectional detail view of the uppermost anchorage mounting of the coil spring;

Fig. 17 is a sectional elevation on line 17—17, Fig. 16;

Figs. 18, 19 and 20 are sectional elevations of different forms of anchorage mountings for a coil spring; and

Fig. 21 is a sectional elevation on line 21—21, Fig. 19.

Referring to Figs. 1 to 14 and 16 and 17, the apparatus shown therein has a pair of spaced apart side frames 1, each consisting of a horizontal member 2 each of which has a pair of feet 3 with resilient pads 4, also a pair of transversely disposed horizontal lugs 5 which are jointed together with dowel pins 6. Each of the members 2 has at one end a vertically disposed L-shaped column bracket 7 both of which have a pair of spaced lugs 8.

There is mounted on the top of the brackets 7 an elongated ironing board 9 which is secured thereto by spaced screws 10, whereby the side frames 1 are held firmly together on the front end of the apparatus. At the rear end of each of the members 2 is a vertically disposed triangular shaped column 11. The rear ends of the side frames 1 are held firmly together by a through bolt 12 which passes through openings 13 in the side frames 1 and through an eccentrically disposed hole 14 in a horizontally disposed barrel 15 the latter having at each end thereof an annular flange 16 against which the side frames 1 abut. One of the flanges 16 has a pintle 18 taking into an opening 19 in one of the side frames 1 (Figs. 4 and 12), whereby a rotatable setting of the barrel 15 can be limited and for the purpose hereinafter referred to.

Pivotedly mounted above and between the side frames 1 is an oblate-ring-shaped actuating arm 21 which has at one end thereof a pair of spaced apart depending arms 22. Disposed near the upper end of each arm 22 is a bearing 23 to accommodate a fixed pin 24 which is rigidly affixed in the apex of the triangular column 11. Both the pins 24 are in axial alignment. Located beneath the rear end of the arm 21 rearwardly of the pivotal mounting thereof is a transversely disposed bridge plate 25 which is rigidly secured to the arm 21 in an oblique angular position. Plate 25 has a through opening 26 to accommodate a ferrule 27 through which passes an electric current cable 28. The angular set of

the plate 25 is such to minimise the bending action of the cable 28 before entering the ferrule 21. Cable 28 thence passes upwardly into a horizontally disposed trough 29 formed integrally with the arm 21, from thence the cable 28 passing to an electric heating element disposed within the heating iron 30.

On the top of the arm 21 is a cover plate 32 secured thereto by spaced set screws 33. Near the front end of the arm 21 are a pair of depending bifurcated lugs 34 each having a slotted groove 35. Upstanding arms 36 take into the grooves 35 and lugs 34. The arms 36 are formed integrally with a H-shaped bracket 37 which is rigidly mounted on the iron 30 and pivotally connected to the lugs 34 by pins 38. Bracket 37 is rigidly secured to the iron 30 by spaced screws 39 with an interposed asbestos washer 40 (Fig. 6).

When the iron is in operation, there will naturally be a layer of air in contact with the under surface of the iron 30, and this air will be at about the same temperature as the heated face of the iron itself. If the iron is brought down parallel to the surface of the ironing board, the high temperature air is suddenly expelled around the periphery of the iron in the form of a blast or puff. Because of the high temperature of the air and nature of the blast or puff, the forward portion of which is directed toward the operator, its effect is both annoying and undesirable.

In order to divert this blast or puff of hot air away from the operator, in accordance with the invention, the iron is so tilted with respect to the ironing board that its forward edge engages the ironing board first and disengages the ironing board last, as the iron is moved into and out of engagement with the work 94. This is accomplished by positioning the iron supporting pivot pins 38 rearwardly of the center of gravity of the iron 30, (Fig. 6) so that the forward edge of the iron will be lower than the rear edge by reason of the resulting tilting of the iron. Obviously, this tilting action may be obtained by other biasing means than the weight of the iron itself.

In opening the iron, the inertia of the iron, since its center of gravity is located forwardly of its pivot suspension, aids the weight of the iron in holding the front edge of the iron against the ironing board. In this manner, the rear edge of the iron opens first, thereby providing a path for the escape of steam and hot gases, which path is directed entirely away from the operator.

Iron 30 is shaped to correspond with that of the ironing board 9 and it has an upstanding surrounding wall 45 upon which is secured a cover plate 46 by spaced screws 47. The iron 30 has partition webs 48 forming compartments to receive therein electrical heating elements 50 to which the cable 28 is electrically connected, also a thermostat 51 (Fig. 8). On the cover plate 46 is mounted thermostat dial 52 having a manually controlled knob 53 (Figs. 1 and 7). When the iron 30 is lifted clear of the ironing board 9 its tilting limit is controlled by the iron 30 engaging with the protuberances 55 associated with the actuating arm 21.

Upon the top of the ironing board 9 is a suitable padding 51 securely held in position by a fabric cover 58 secured to the ironing board 9 by a cord 59 and upon which is placed the article or material 94 to be ironed.

Near the bottom end of each depending arm 22 is a fixed trunnion pin 60 each having pivotally mounted thereon one limb 62 of an L-shaped

lever 63. Both limbs 62 are jointed together by a transverse bar 64 located near the heels 65 of the lever 63. The toe ends 66 of the other limbs 67 of the L-shaped levers 63 support a bridge pin 68 on which is pivotally mounted a connector 69 to which is connected one end of a pull-rod 70 (Figs. 4, 5 and 10). The rod 70 lies centrally within the arm 21 and its other end projects through a vibration absorbing ferrule 71 secured in a through opening 72 (Fig. 6) in the front end of the arm 21 (Fig. 6). Rod 70 carries an adjustable stop 73 (Fig. 10) having a vibration absorbing pad 74 thereon. Stop 73 limits the outward withdrawal stroke of the rod 70. On the outer end of the rod 70 is a manually operable knob 75 with a vibration absorbing pad 76 thereon, so that on the rod 70 completing its inward stroke the pad 76 will abut the front end of the arm 21 and thus avoid any shock to the operator's hand. In each heel 65 of the L-shaped lever 63 is a pivot pin 77, each supporting a radial link 78. Both links 78 together supports a shaft 79 and forms the upper anchorage for the force producing member say the coil spring 80.

Positioning of the shaft 79 can be radially adjusted by adjusting screws 81 taking against the links 78, the screws 81 being mounted in the bridge bar 64 (Figs. 4, 16 and 17) for the purpose hereinafter referred to. Shaft 79 has a ferrule 82 having an annular groove 83 in which takes the upper end hook 84 of the coil spring 80. The inner radius of the hook 84 is greater than that of the ferrule 82, so that the ferrule 82 will roll upon the hook 84. The lower end hook 85 of the coil spring 80 engages in the annular groove 86 of a ferrule 87 on a shaft 88 carried in the radial arms 89 formed integrally with the barrel 15. The inner radius of the hook 85 is greater than that of the ferrule 87 (Figs. 4, 5 and 12), so that the ferrule 87 will roll upon the hook 85.

Axial centre 89 of shaft 88 is set eccentrically to the axial centre 90 of the trunnion pins 60 in a vertical plane, so that the L-shaped lever 63 and the coil spring 80 are prevented from moving automatically when in a stationary position.

Affixed to one of the triangular shaped columns 11 is a resilient buffer 91 against which engages the L-shaped lever 63 when the latter is operated. Buffer 91 is shielded by a guard plate 92 transversely disposed between the column 11 and secured thereto by screws 93. Such shield also prevents an article or material on the ironing board from contacting the mechanism of the apparatus.

On reference to Figs. 3, 10, 12, 13, 14, 16 and 17 it will be seen how the coil spring 80 is correctly positioned so as to produce a full effective result. By adjusting the position of the barrel 15 before it is locked in the side frames 1 the axial centres of the shaft 79, shaft 88 and trunnion pin 60 are brought into alignment. By adjusting the position of the shaft 79 by the adjusting screws 81 the tension of the coil spring 80 can be increased or decreased as desired, and by adjusting the rod 70 in connector 69 a position is found whereby the force producing member suitably balances the iron about the pivotal mounting on pins 24 throughout its range of opening up and closing down, and as the coil spring 80 and appurtenances are moving from extreme operated positions (Figs. 13 and 14) the coil spring 80 will vary the rate of opening the iron as desired owing to the oppositely disposed ferrules 82 and 87 rolling upon the respective hook ends 84 and 85 therefor.

In operation, the article or material 94 to be ironed is placed upon the top of the cover 58 when the iron 30 is in raised position (Fig. 2) and held therein by the force producing member, say the coil spring 80, exerting a pull on the depending arms 22 of the actuating arm 21, the arms 22 resting against the buffer 91. The operator now takes hold of the knob 15 and pulls the actuating arm 21 downwardly until the iron makes contact with a sliding motion with an article or material to be ironed, and then pulls outwardly the rod 10 a distance or until the stop 73 engages with the ferrule 14 (Fig. 3 and dotted position in Fig. 6), the front or leading edge 43 of the iron 30 making contact with the article or material 94 on the ironing board 9 before the iron 30 will rest entirely upon the article or material 94 (Figs. 3 and 6). The iron 30 is kept automatically in ironing press position on the article or material 94 through the friction of the apparatus, or in the case of articles abnormally thick to that to which the apparatus is adjusted by the operator meanwhile holding the knob 15.

Should there by any bulge or bulges 95 in the article or material 94 (Fig. 7) a twist influence is imparted to the actuating arm 21 through the iron 30 tending to take up an oblique position relative to the ironing board 9 (see dotted line 96 Fig. 7), but the iron is firmly attached to the H-shaped bracket 37 which bracket is non-yieldable though pivotally connected to the oblate-ring-shaped actuating arm 21 which by its shape and pivotal connection to the fixed pins 24 is structurally adapted to resist the twisting influence imparted by the bulge 95; and the ironing board 9 is non-yieldably secured to the brackets 1 of the members 2 of the side frames 1 which are jointed together by dowel pins 6 and held firmly together by a bolt 12 abutting the flanges 16 of the barrel 15 against the side frames 1, whereby the side frames 1 so jointed together are structurally adapted to resist the twisting influence imparted by the bulge 95, and thereby the iron 30 is prevented from taking up an oblique position relative to the ironing board 9 as indicated by the dotted line 96 (Fig. 7) and thereby pressure is concentrated upon the bulge 95, until it is pressed down so that the bulge or bulges 95 will be removed from the article or material 94.

When the actuating arm 21 has been pulled down and as the rod 10 is being pulled outwardly the shaft 79 of the coil spring 80 is drawn over from the position it occupied in a vertical plane situated rearwardly of the fixed pins 24 to take up a position on the opposite side of the fixed pins 24 (Fig. 3), so that the tension of the coil spring 80 will be transferred to assist in pressing the iron downwardly upon the ironing board 9 when ironing the article or material 94.

On completion of ironing the article or material 94 the operator pushes the rod 10 inwardly until the pad 16 engages with the front end of the actuating arm 21; then the coil spring 80 automatically lifts or assists to lift the iron 30 from the ironing board 9. When the iron 30 is to be lifted as above described, and as it is about to be lifted, the front edge 43 thereof lifts slower from the article or material 94 while the rear edge 97 thereof has lifted faster clear of the article or material 94, so that exit is formed for the escape of any gases such as steam emanating from the article or material 94, such gasses passing from the apparatus in a direction away from the operator. The actuating arm 21 with the iron 30 thereon continues lifting until the 75

lever 63 comes to rest in dead balance just before reaching the buffer 91 or takes against the buffer 91, and is held in such position by the force of the spring 80.

In Fig. 15 is shown a modified construction of the apparatus to that above described with reference to the apparatus shown in Figures 1 to 14 and 16 and 17 of the drawings. Similar parts of the apparatus shown in such figures to those shown in Fig. 15 are marked in Fig. 15 with similar reference numerals. In said modification the columns 7 are shown supporting an angularly set ironing board 99 which is pivotally mounted centrally thereon as at 100 and bearing upon equally spaced coil springs 101 which are supported upon the lugs 102 associated with the columns 7. The angular disposition of the ironing board 99 is towards the operator. Further, the iron 30 instead of being pivotally mounted on the actuating arm 21 is rigidly secured thereto, but set at an angular disposition corresponding almost to that of the ironing board 99, the latter having a slight obtuseness so that the front edge 43 of the iron 30 will make contact with the article or material 94 as above described. The operation of the said modified apparatus is as before described with reference to the apparatus shown in Figures 1 to 14 and 16 and 17 with the exception that on the iron 30 having made contact with the article or material 94 it then slides forwardly towards the operator while setting down upon the entire surface of and during the compression and expansion of the article or material 94 to be ironed, so that a smoother effect is given to the ironing action of the iron 30.

Referring to Figs. 18 to 21, in these are shown various forms of mounting of the coil spring 80. In each of the Figs. 18 and 19, the shaft 79 is rigidly affixed, but rotatably affixed in Fig. 20 in the heels 65 of the levers 63 although such shaft can be mounted as before described. The shaft 79 carries the ferrule 82 as shown in Figs. 18, 19 and 21, the ferrule 82 having an annular groove to receive the hook end 84 of the coil spring 80. In Fig. 18 the lower end of the spring 80 supports a screw-threaded nut 104 of a bolt 105, the head 106 of the bolt 105 carrying a small coil spring 107 having a hook 108 which embraces the ferrule 87 of the shaft 88 associated with the barrel 15. The bolt 105 has a through opening 109 to receive a tommy-bar, so that on turning the bolt 105 tension on the coil springs 80 and 107 can be adjusted. In Fig. 19, the lower end of the coil spring 80 supports a depending bolt 110 by its head 111. The bolt 110 is screw-threaded into the shaft 88. Bolt 110 also has an opening 112 for receiving a tommy-bar, so that the bolt 110 can be rotated for the purpose of adjusting the tension of the coil spring 80. In Fig. 20 the upper end of the coil spring 80 is suspended from the head 113 of a screw-threaded bolt 114, the shank of the bolt 114 passing freely through an opening 115 in the shaft 79 and said shank having a nut 116. The lower hook 85 of the coil spring 80 takes around the ferrule 87 of shaft 88. By turning the nut 116 the tension of the coil spring 80 can be adjusted.

It will be understood that the ironing press apparatus for clothes, textile fabrics or the like according to the invention has a lever to which is attached the iron, the said lever with the iron thereon being pivotally balanced by a force producing member, consisting of a coil spring, so that suitable balancing of the iron throughout its range of opening up and closing down will

be effected, and that when the position of the force of the said member is altered relative to the pivotal connection of the said lever, said iron will thereby be caused to exert pressure on the article or material being ironed. The force of the spring force producing member is varied, so that the force of the said member is increased or decreased as desired for pressing the iron downwardly on the article or material being ironed. Further, in connection with the ironing press apparatus according to the invention the iron in its closure on the clothes or material to be ironed provides a partly sliding motion and also that hot air or steam is not directed to the operator and that on the iron leaving the clothes or material after ironing operation thereof the hot air or steam is not directed to the operator. Again, in the ironing press apparatus according to the invention the lever with its associated iron is normally held in raised position and held therein by the force of the said member, and there is a slideable rod associated with the lever, the latter being manually operated for ironing press purposes by an operator pulling the lever downwardly until the iron makes contact with a part sliding motion with the clothes or material to be ironed and then by pulling the slideable rod outwardly, the force of the said member lifting or assisting in lifting the lever with its associated iron to raised position thereof when the ironing operation has been completed upon the operator pushing the slideable rod inwardly in relation to the lever.

What I claim as my invention and desire to secure by Letters Patent is:

1. Ironing press apparatus for clothes, textile fabrics or the like having a framing, an ironing board on the top of the forward portion of said framing, a manually operable actuating arm pivoted to said framing at the rear portion thereof and extending forwardly toward said ironing board, an iron carried on the under side of said actuating arm at the forward portion thereof and movable into engagement with said ironing board, said iron and said ironing board being pivotally movable at least one with respect to the other, the axes of both of said pivots being parallel to each other and perpendicular to a forwardly and rearwardly extending vertical plane, and biasing means yieldingly acting to bring the forward edge of said iron into engagement with said ironing board before the rear edge of said iron comes into engagement therewith.

2. Ironing press apparatus according to claim 1, in which the framing has a pair of spaced apart side frames each consisting of a horizontal member each of which has a pair of feet with resilient pads also a pair of transversely disposed horizontal lugs which are jointed together with dowel pins and each said horizontal member has at one end a vertically disposed L-shaped column bracket both of which have a pair of spaced lugs.

3. Ironing press apparatus according to claim 1, in which the framing comprises a pair of spaced apart side frames, each side frame having column brackets thereon at the upper portion thereof, and in which the ironing board is mounted on top of said column brackets and is secured thereto by spaced screws so that said spaced apart side frames of the framing are held firmly together on the front end of the apparatus.

4. Ironing press apparatus according to claim

1, in which the framing has a pair of horizontal members at the rear end of each of which is a vertically disposed triangular shaped column.

5. Ironing press apparatus according to claim 1, in which said framing comprises a pair of spaced apart side frames; a horizontal through bolt interconnecting said side frames and firmly holding them in said spaced relationship; a tension member having one end thereof connected to means carried by said actuating arm for movement therewith to counter-balance the weight of said actuating arm and said iron carried thereby, the other end of said tension member being connected to a barrel eccentrically and rotatably mounted on said through bolt, said barrel having a flange at each end abutting against said side frames, one of said flanges having a pintle extending into an opening in one of said side frames whereby a rotatable setting of said barrel can be limited.

6. Ironing press apparatus according to claim 1, wherein said framing comprises a pair of triangular columns, and in which the actuating arm is of oblate-ring-shape at one end of which are a pair of spaced apart depending arms, a bearing is disposed near the upper end of each said depending arms for a fixed pin, each pin being rigidly affixed in the apex of one of said triangular columns both said pins being in axial alignment.

7. Ironing press apparatus according to claim 1, in which said iron is electrically heated, and in which the actuating arm has located beneath its rear end and rearwardly of the pivotal mounting thereof a transversely disposed bridge plate which is rigidly secured to said arm in an oblique angular position, a ferrule being carried in an opening in said plate adapted for passage therethrough of an electric current cable for supplying electric current for heating said iron and the angular set of the said plate being such as to minimise bending action of the said cable before entering the said ferrule, the said cable passing upwardly from the said ferrule into a horizontally disposed trough formed integrally in the said arm from which trough the cable passes to electric heating means disposed within the iron.

8. Ironing press apparatus according to claim 1, in which the actuating arm has on its top a cover plate secured thereto by set screws, near the front end of the actuating arm are a pair of depending bifurcated lugs each having a slotted groove, upstanding arms which extend into the grooves and lugs, said upstanding arms being formed integrally with an H-shaped bracket which is rigidly mounted on the iron and pivotally connected to the lugs by pins, the said bracket being rigidly secured to the iron by spaced screws with an interposed asbestos washer.

9. Ironing press apparatus according to claim 1, in which the iron is pivoted to the actuating arm and the center of gravity of the iron is offset forwardly of the centre of its pivotal connection to said arm thereby biasing the iron, so that its front edge will make contact with an article or material on the ironing board before the iron rests entirely upon the whole surface of the said article or material on the ironing board.

10. Ironing press apparatus according to claim 1, in which the iron is electrically heated and is shaped to correspond with the shape of the ironing board and the iron has an upstanding surrounding wall upon which is secured a cover plate by spaced screws and the iron has partition webs forming compartments to receive therein the

electrical heating means and a thermostat, the said cover plate having mounted thereon a thermostat dial which has a manually controlled knob, the iron when it is lifted clear of the ironing board engaging with protuberances associated with the actuating arm.

11. Ironing press apparatus according to claim 1, in which on the top of the ironing board is a padding securely held in position by a fabric cover secured to the ironing board by a cord and upon which is placed the article or material to be ironed.

12. Ironing press apparatus according to claim 1, in which the actuating arm has at its rear end a pair of spaced apart depending arms and near the bottom end of each depending arm is a fixed trunnion pin each having pivotally mounted thereon one limb of an L-shaped lever, both said limbs being jointed together by a transverse bar located near the heels of the said lever, the toe ends of the other limbs of the said levers supporting a bridge pin on which is pivotally mounted a connector to which is connected one end of a pull-rod which lies centrally within the actuating arm, the other end of the pull-rod projecting through a vibration absorbing ferrule secured in a through opening in the front end of the actuating arm.

13. Ironing press apparatus according to claim 1, in which the actuating arm has centrally within it a pull-rod which carries an adjustable stop having a vibration absorbing pad thereon, the said stop limiting the outward withdrawal stroke of the rod, the latter having on its outer end a manually operable knob with a vibration absorbing pad thereon, so that on the rod completing its inward stroke the pad will abut the front end of the actuating arm and thus avoid any shock to the operator's hand; a pivot pin is disposed in each heel of an L-shaped lever which is pivotally mounted on trunnion pins on spaced apart depending arms at one end of the actuating arm, each of the said pivot pins supporting a radial link, both of the said links together supporting a shaft which forms the upper anchorage for a coil spring.

14. Ironing press apparatus according to claim 1, in which a pivot pin is disposed in each heel of an L-shaped lever which is pivotally mounted on trunnion pins on spaced apart depending arms at one end of the actuating arm, each of the said pivot pins supporting a radial link, both of the said links together supporting a shaft which forms the upper anchorage for a coil spring, the said shaft being radially adjusted by adjusting screws taking against the links, the said screws being mounted in a bridge bar, the said shaft having a ferrule which has an annular groove in which takes an upper end hook of the coil spring, the inner radius of the said hook being greater than that of the ferrule so that the said ferrule will roll upon the said hook and the lower end hook of the coil spring engages in an annular groove of another ferrule on a shaft carried by radial arms formed integrally with a horizontally disposed barrel associated with the rear ends of spaced apart side frames of the framing, the inner radius of the lower end hook of the coil spring being greater than that of its cooperative ferrule, so that the said ferrule will roll upon the latter hook.

15. Ironing press apparatus according to claim 1, in which the axial centre of a shaft carried by radial arms formed integrally with a horizontally disposed barrel associated with the rear ends of

spaced apart side frames of the framing is set eccentrically to the axial centre of fixed trunnion pins near the bottom end of spaced apart depending arms at one end of the actuating arm, so that an L-shaped lever which is pivotally mounted on said trunnion pins and a coil spring whose upper anchorage is a shaft associated with said lever by pivot pins and radial links are prevented from moving automatically when in a stationary position.

16. Ironing press apparatus according to claim 1, in which the framing has a pair of horizontal members at the rear end of each of which is a vertically disposed triangular shaped column, one of which has affixed thereto a resilient buffer against which engages an L-shaped lever pivotally mounted on trunnion pins on spaced apart depending arms at one end of the actuating arm, when the said lever is operated, the said buffer being shielded by a guard plate transversely disposed between the said triangular shaped columns and secured thereto by screws, the said guard plate also preventing articles or materials being ironed entering the mechanism of the apparatus.

17. Ironing press apparatus according to claim 1, in which a coil spring has for its upper anchorage a shaft supported by radial links, the latter being carried on a pivot pin in each heel of an L-shaped lever which is pivotally mounted on trunnion pins on spaced apart depending arms at one end of the actuating arm, the said spring being correctly positioned so as to produce a full effective result thereof by radially adjusting the said shaft by screws which bear against the said links so that the force of the said spring can be increased or decreased as desired.

18. Ironing press apparatus according to claim 1, in which the framing of the apparatus has a pair of spaced apart side frames, a horizontally disposed barrel associated with said side frames, a supported shaft forming the upper anchorage of a coil spring and a lower anchorage shaft for said spring carried by radial arms formed integrally with said barrel, the said barrel being adjustable before it is locked in the side frames, so that the axial centres of the said supported shaft, the said shaft carried by the radial arms, and fixed trunnion pins near the bottom end of spaced apart depending arms at one end of the actuating arm can be brought into alignment, so that when the said coil spring and its appurtenances are moving from extreme operated positions the said coil spring will vary the rate at which the iron is upraised and/or lowered as desired owing to oppositely disposed ferrules one being carried on the said upper anchorage shaft and the other being carried on the lower anchorage shaft for said coil spring rolling upon the respective hook ends of the said coil spring connected to the said ferrules.

19. Ironing press apparatus according to claim 1, in which should the article or material to be ironed on the ironing board have any bulge or bulges a twist influence can be imparted to the actuating arm through the iron tending to take up an oblique position relative to the ironing board, and said twist influence of the said arm will re-act upon the iron thereby imparting extra pressure upon the bulge or bulges, so that the said bulge or bulges will be removed from the article or material.

20. Ironing press apparatus according to claim 1, in which the actuating arm has a pull-rod, the said arm when it is pulled downwardly and

the pull rod is pulled outwardly of the said arm an upper anchorage shaft for a coil spring supported by radial links associated with a pivot pin in each heel of an L-shaped lever will be drawn over from the position it occupied in a plane situated rearwardly of axially aligned fixed pins to take up a position on the opposite side of such pins, so that the force of the coil spring will be transferred to assist in pressing the iron downwardly upon the ironing board during ironing of the article or material.

21. Ironing press apparatus according to claim 1, in which by the front edge of the iron in the lifting off the iron by the actuating arm lifts slower from the article or material being ironed while the rear edge of the iron has lifted faster clear of the article or material an exit is formed for the escape of any gases such as steam emanating from the article or material, such gases passing from the apparatus rearwardly in a direction away from the operator.

22. Ironing press apparatus according to claim 1, in which the actuating arm with the iron thereon is lifted from the ironing board until an L-shaped lever takes against a resilient buffer and is held in such position by the tension of a coil spring.

23. Ironing press apparatus of the class described, comprising: a framing; an ironing board disposed on the forward portion of said framing and inclined at an angle with respect to a horizontal plane, said ironing board being pivotally mounted and rotatable about an axis perpendicular to a forwardly and rearwardly extending vertical plane; spring means urging said ironing board toward a predetermined normal position, which is forwardly and downwardly inclined; a forwardly extending manually operable actuating arm having one end portion thereof pivoted to the rear portion of said framing; an iron carried by said arm at the forward portion thereof and movable into engagement with said ironing board, said iron, upon initial engagement with said ironing board being inclined at a similar but greater angle with respect to a horizontal plane than said ironing board for causing the forward edge of said iron to engage said ironing board before the rear edge thereof comes into engagement therewith.

24. Ironing press apparatus according to claim 23, in which on the iron having contacted with the article or material on the ironing board

5
10

it then slides forwardly towards the operator while settling down upon the entire surface and during compression and expansion of the article or material to be ironed, so that a smoother effect is given to the ironing action of the iron.

25. Ironing press apparatus according to claim 1, further comprising arm counterbalancing tension spring means interconnecting means carried by said framing and means carried by said arm for movement therewith, said spring means comprising two coil spring sections interconnected by a threaded nut and bolt, said bolt having a through opening to receive a tommy-bar, so that on turning the said bolt, the tension of said coil spring sections is adjustable.

26. Ironing press apparatus according to claim 1, further comprising spring anchorage means carried by said framing, spring anchorage means carried by said arm for movement therewith, arm counterbalancing coil spring tension means interconnecting said anchorage means, an apertured shaft forming a part of said anchorage means, and a headed bolt in threaded engagement with said shaft aperture, said bolt head being engaged by one end of said spring, said bolt having a depending bolt by its head, the said bolt being screw-threaded into a shaft and the said bolt also having an opening to receive a tommy-bar, so that the bolt can be rotated to adjust the tension of the said coil spring.

27. Ironing press apparatus according to claim 1, further comprising spring anchorage means carried by said framing, spring anchorage means carried by said arm for movement therewith, arm counterbalancing coil spring tension means interconnecting said anchorage means, an apertured shaft forming a part of said anchorage means, a headed bolt passing freely through said shaft aperture, said bolt head being engaged by one end of said spring, and a nut in threaded engagement with the free end of said bolt, the tension of said spring being adjustable by turning the said nut.
